DEVICE FOR ADMINISTERING A BIOLOGICAL PRODUCT

Willy Lhoest, Rixensart, and Eloi Van Hoye, Weert-St.-Georges, Belgium, assignors to Recherche et Industrie Therapeutiques, Genval, Belgium

Filed Aug. 2, 1974, Ser. No. 493,879

Term of patent 14 years

Int. Cl. D24—02

U.S. Cl. D83—12 A

FIG. 1.

FIG. 5.

FIG. 2.

FIG. 3.

FIG. 6.

FIG. 4.

FIG. 1 is a front elevation of a device for administering a biological product of the invention;

FIG. 2 is a rear elevation of the device of FIG. 1;

FIG. 3 is a left side elevation of the device of FIG. 1;

FIG. 4 is a right side elevation of the device of FIG. 1;

FIG. 5 is a top plan view of the device of FIG. 1; and

FIG. 6 is a bottom plan view of the device of FIG. 1.

We claim:

The ornamental design for a device for administering a biological product, as shown.
